TRACK WRENCH

Filed May 31, 1930

Inventor

Bert Graham

Glenn L. Fish

Attorney

UNITED STATES PATENT OFFICE

BERT GRAHAM, OF IONE, WASHINGTON

TRACK WRENCH

Application filed May 31, 1930. Serial No. 457,975.

My invention relates to track wrenches and more particularly to a wrench device for bolting up rail joints on a railroad track. Certain objects of the invention are to provide a wrench comprising a spacer bar with track engaging arms and a worm shaft adapted for slideable, axial and rotary movement with a wrench jaw whereby all the nuts of a rail joint may be either set up or removed at one setting of the device as a whole. Further objects are to provide adjustable clamp means for securing the track engaging arms to the track rails, means for connecting the ends of the spacer bar to the track ties, and means for reversing the direction of the rotary and axial movement of the worm shaft.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:

Figure 1 is a view in perspective showing the application of the device;

Fig. 2 is a view in transverse vertical section of the same taken substantially on a broken line 2, 2 of Fig. 1;

Fig. 3 is a detail view in central vertical section of the ratchet wrench portion of the device;

Fig. 4 is a detail view in elevation showing the handle connection with the worm shaft; and

Fig. 5 is a fragmentary view showing the rail engaging end of one of the track engaging arms in engagement with a rail.

Referring to the drawings throughout which like reference numerals indicate like parts, the numeral 5 designates a rail joint that is spiked to a number of ties 6 in the usual manner. My device comprises a pair of arms 7 whose rail engaging end portions are each provided with a shoulder 8 and which end portions have a series of square cut teeth 9 on their upper edge portions. Said shoulders are adapted to fit snugly against one side of the rail tread and a clamping

plate 10 is provided with a slot 11 which is adapted to slip over the toothed end portions of said arms and to rest between said teeth in snug engagement with the other side of the rail tread as shown in detail in Fig. 5 of the drawings. Said teeth and plate thus provide adjustable means whereby different sizes of rails may be clamped between the plate and shoulder as will be understood.

The remote ends of the arms 7 are slightly curved downward and are each provided with a hole 12 and said holes are adapted to receive a pin 13 formed on end blocks 14. Said end blocks are secured in fixed spaced relation by an upper and a lower spacer bar 15 whose end portions are welded, brazed or otherwise fixed to the respective under and upper sides of said blocks. Said end blocks are each provided with a hole passing upwardly therethrough and through the end portions of the spacer bars fixed thereto. Said holes are adapted to receive the shank or upright portions 16 of claw members whose bottom ends have a spike point 17 and whose offset or horizontal portions 18 are likewise provided with a point 19 at their ends. Thus when the points of said claw members are imbedded in the ties 6 as shown in the drawings the device as a whole is braced in readiness for work. Said spacer bar members may be adjustably positioned and secured on the shank portions of said claw members by means of set screws 20.

A traveler block 21 is slidably disposed between the upper and lower spacer bars 15 with said bars fitting into slots 22 respectively provided in the upper and lower sides of said traveler. Said traveler block is provided with a wormed hole transversely of the spacer bars which is arranged to receive a worm shaft 23. A handle 24 is fixedly secured to the outer end of said worm shaft and a ratchet member 25 has its hub fixed to the inner end of said worm while a wrench jaw member 26 is detachably set into the opposite hub portion of said ratchet member. A wrench casing 27 envelopes the ratchet wheel portion of said ratchet member, as shown in detail in Fig. 3, and a double acting pawl 28 is centrally pivoted within a hollow portion

29 of said wrench casing. Said pawl has a central upstanding finger 30 and a push rod 31 has its central portion connected through said finger and its ends extending exteriorly 5 of said casing. A bow spring 32 engages said finger and is adapted to retain either end of the pawl in engagement with the ratchet as will be understood. To reverse the ratchet the push rod is forced to the other side carrying the finger past the spring and pivotally carrying the other end of the pawl into engagement with the ratchet.

10 In the use of my device, assuming that same is connected to the rail and ties as shown in 15 Figs. 1 and 2 of the drawings, the jaw 26 is brought into engagement with a nut of the rail joint by turning the handle 24 which is used for quick movement of the worm shaft 23. Then by means of a wrench handle 33, 20 secured into a sleeve of the wrench casing 27, the ratchet 25 is turned carrying the wrench jaw and worm shaft around and thus setting up on the nut. The pitch of the worm shaft is made substantially the same as the pitch 25 of the ordinary bolts used for connecting rail joints so that the worm will move axially at the same rate as does the nut and the wrench jaw will therefore follow up the nut as it is tightened into place.

30 After setting up on one nut the wrench jaw may be quickly shifted to the next nut by turning the handle 24 in a counter clockwise direction, sliding the traveler block 21 along the proper distance and setting up as before. To remove a tightened nut it is merely necessary to reverse the pawl 28 by means 35 of the push rod 31. It will thus be apparent that I have provided a handy and forceful means whereby all the nuts may be either set 40 up or removed from one rail joint at one setting of the device as a whole.

Having thus described my invention, it being understood that minor changes may be resorted to in its construction and arrangement without departing from the scope and spirit of the invention, what I claim and desire to secure by Letters Patent of the United States is:—

50 A track wrench having in combination a pair of track engaging arms, a shoulder and teeth for the track engaging ends of said arms, a slotted clamp plate adapted to engage said teeth whereby different sizes of rails 55 may be clamped against said shoulder, a block member pivotally connected to each of the remote ends of said track engaging arms, a pair of spacer bars having their ends secured to the under and upper sides of said blocks whereby the track engaging arms are held in 60 spaced apart relation, claw members adjustably connected to said blocks and adapted to engage the ties of a railroad track, a traveler block slidably disposed between the upper and lower spacer bars, a worm shaft 65 passing through said traveller block and hav-

ing a handle on its outer end, a ratchet member having its hub connected to the inner end of said worm shaft, a track engaging wrench jaw member detachably connected to the oppositely aligned hub of said ratchet member, 70 a casing enveloping the ratchet wheel portion of said member and adapted for revolvable movement thereon, a double acting pawl pivoted within said casing, a central upstanding finger for said pawl, a push rod pivotally connected to said finger and having both of its ends extending exteriorly of the casing whereby the pawl may be pivotally moved to bring either of its ends into engagement with the ratchet, a bow spring engaging said finger 80 whereby either end of the pawl is retained in engagement with the ratchet, and a handle connected to the ratchet casing.

10 In testimony whereof I affix my signature.

BERT GRAHAM.
